SUPPORT FOR A GASOLINE DISPENSER OR THE LIKE

Hal C. Hartsell, Jr., Rte. 9, Evergreen Drive, Winston-Salem, N.C. 27106, and David D. Tompkins, 10350 Olentangy River Road, Worthington, Ohio 43085

Filed Sept. 23, 1969, Ser. No. 19,258

Term of patent 14 years

Int. Cl. D20—99

U.S. Cl. D52—2

FIG. 4

FIG. 1

FIG. 3

FIG. 2

FIG. 5

FIG. 8

FIG. 6

FIG. 7

FIG. 1. is a perspective view of a support for a gasoline dispenser or the like showing our new design;

FIG. 2 is a right side elevational view;

FIG. 3 is a front elevational view;

FIG. 4 is a top plan view;

FIG. 5 is a perspective view of a support of a gasoline dispenser or the like showing another form of our new design;

FIG. 6 is a front elevational view;

FIG. 7 is a left side elevational view; and

FIG. 8 is a top plan view.

We claim:

The ornamental design for a support for a gasoline dispenser or the like, as shown and described.
